Attorney:

UNITED STATES PATENT OFFICE.

DANIEL R. LANDIS, OF CHICAGO, ILLINOIS.

CURTAIN STRETCHER.

1,403,505.

Specification of Letters Patent. Patented Jan. 17, 1922.

Application filed February 2, 1920. Serial No. 355,665.

To all whom it may concern:

Be it known that I, DANIEL R. LANDIS, a citizen of the United States, and a resident of the city of Chicago, county of Cook, and 5 State of Illinois, have invented certain new and useful Improvements in Curtain Stretchers, of which the following is a specification.

My invention relates to new and useful 10 improvements in curtain stretchers, and has for its object the provision of a curtain stretcher simple in structure, economical in manufacture, and highly efficient in use.

Another object is the provision of a curtain 15 stretcher which may be quickly and thoroughly cleaned and washed.

Another object is the provision in a curtain stretcher of means for preventing the warping of the same after washing.

20 Other objects will appear hereinafter.

The invention consists in the combinations and arrangements of parts hereinafter described and claimed.

The invention will be best understood by 25 reference to the accompanying drawings forming a part of this specification, and in which,

Fig. 1, is a side elevational view of the invention, and

30 Fig. 2, is a sectional view of one of the bars used in the invention.

My invention comprises a curtain stretcher having longitudinally extending bars or rails 5 and 6 and cross bars 7 and 8 connecting 35 the longitudinally extending members and securely clamped thereto in adjusted positions by means of adjusting clamps 14. The longitudinal rails and cross bars are provided along their inner edge with projecting pins or nails 9, upon which the curtain 40 is impinged when the same is being dried after washing.

With curtain stretchers as now used, the fibrous surface of the wooden curtain 45 stretchers affords a gathering place for soap, starch and dirt. It is practically impossible to remove all of this accumulation from the curtain stretcher and the cleaning of the curtain stretcher is rendered more difficult 50 by the pins which project through the frame.

The wood forming the curtain stretcher proper also absorbs the die used upon the curtain, with the result that when a clean white curtain is placed on the stretcher, the 55 coloring matter which has been absorbed by the wood and the soap, dirt and starch

which are clinging to the same are transferred to the curtain upon its coming in contact therewith, thereby staining and soiling it. Also when the curtain stretcher is formed 60 from wood the same requires a considerable time for drying after washing, which is an undesirable feature in a curtain stretcher. To obviate these difficulties, I provide a covering 8' which is formed from some metallic 65 substance, preferably aluminum or tin and secured around the wooden portion of the curtain stretcher. In assembling the covering 8' upon the members 7 and 8 and 5 and 6, I turn one of the ends 10 inwardly into 70 a recess or groove 12 formed in the rail or bar, as shown in Fig. 2, and fold the covering over said bar to the corner 15. Pins 9 are then driven through the wooden portion and through the covering 8'. The member 75 8' is then wrapped completely around the rail or bar and its opposite end is then inwardly turned so as to seat in the groove 12. The covering 8', therefore, engages the heads of the pins or nails 9 and serves as a 80 backing for them so as to prevent the same from becoming loose or being moved outwardly relatively to the bar or rail. With 85 curtain stretchers as now in use, this is a common fault, inasmuch as the pins or nails become loosened in the bar or rail through use. Elongated pieces of metal 11 are used for retaining the ends of the member 8' within the groove 12 and consist of metallic strips which are driven into the groove so 90 as to wedge the ends of the member 8' into close engagement with the groove 12.

With a curtain stretcher having side rails and cross members covered with this metallic coating, the curtain stretcher is prevented 95 from warping, inasmuch as no water or liquid of any kind reaches the wooden portion. Also the metallic covering presents a surface which is quickly and easily washed and to which the starch will not readily 100 adhere and into which the die used upon the curtains will not penetrate.

While I have illustrated and described the preferred form of construction for carrying my invention into effect, this is capable of 105 variation and modification without departing from the spirit of the invention. I, therefore, do not wish to be limited to the precise details of the construction set forth, but desire to avail myself of such variations 110 and modifications as come within the scope of the appended claims.

Having described my invention, what I claim as new and desire to secure by Letters Patent is:

1. In a curtain stretcher, a metallic covering for the bars and rails thereof; and pins or nails driven through said bars or rails adjacent one of their edges and projecting through one side of said covering and having heads bearing against the opposite inner side of said covering, substantially as described.
2. A curtain stretcher having side rails and cross bars; pins projecting through said side rails and cross bars adjacent one of their edges; and metallic means for covering said rails and cross bars, the curtain-engaging end of said pins projecting through one portion of said covering and the opposite end of said pins bearing against another portion of said covering, substantially as described.
3. A curtain stretcher having rails and cross bars, each being provided with longitudinally extending grooves, in one side; metallic means for covering said bars and side rails, the ends of said covering being turned inwardly to engage in said grooves; and metal strips for locking said ends of said covering in said grooves, substantially as described.
4. A curtain stretcher comprising side rails and cross bars, each having a longitudinally extending groove formed in one side thereof; pins projecting through said rails and said bars adjacent one edge thereof; means for covering said rails and said bars with a metallic coating, the curtain-engaging end of said pins projecting through said covering; and an angularly turned portion at the opposite ends of said covering adapted for engagement in said groove, substantially as described.

5. A curtain stretcher comprising side rails and cross bars, each having a longitudinally extending groove formed in one side thereof; pins projecting through said rails and said bars adjacent one edge thereof; means for covering said rails and said bars with a metallic coating, the curtain engaging end of said pins projecting through said covering; an angularly turned portion at the opposite ends of said covering adapted for engagement in said groove; and wedge strips for locking said angularly turned portion in position in said groove, substantially as described.

6. A curtain stretcher having side rails and cross bars; metallic means for covering said rails and cross bars; and pins projecting through said rails and bars, one end of said pins projecting through said covering and the opposite end bearing against the inside of said covering, which serves to retain said pins in their assembled position in said rails or bars, substantially as described.

7. A curtain stretcher having side rails and cross-bars; metallic means surrounding said rails and cross-bars; pins projecting through said rails and bars and through the metallic means at one side thereof, the said pins having heads which bear on the opposite side of said rails and bars and on the inside of said metallic means; and inturned edges on the metallic means which are fastened in the side of the rail or bar opposite to said pins, substantially as described.

In testimony whereof I have signed my name to this specification in the presence of two subscribing witnesses.

DANIEL R. LANDIS.
